DISPOSABLE COVER FOR LARYNGOSCOPE

Jack Bauman, Santa Monica, Calif.
(1502 San Remo Drive, Pacific Palisades, Calif. 90272)

Filed May 27, 1975, Ser. No. 580,696

Term of patent 14 years

Int. Cl. D24—02

U.S. Cl. D83—12 R

FIG 1

FIG 2

FIG 3

FIG 4

FIG 5

FIG 6

FIG. 1 is an elevational view of one side of a disposable cover for laryngoscope, showing my new design;

FIG. 2 is a top plan view;

FIG. 3 is an elevational view of the other side, the cover being inverted relative to FIG. 1;

FIG. 4 is a bottom plan view;

FIG. 5 is an elevational view of the left-hand end of FIG. 1; and

FIG. 6 is an elevational view of the right hand end of FIG. 1.

I claim:

The ornamental design for a disposable cover for laryngoscope, as shown and described.
